UNITED STATES PATENT OFFICE.

ALBERT C. CALKINS, OF LOS ANGELES, CALIFORNIA, ASSIGNOR TO
FREDERICK W. BRAUN, OF SAME PLACE.

CUPEL-MACHINE.

SPECIFICATION forming part of Letters Patent No. 637,081, dated November 14, 1899.

Application filed July 13, 1899. Serial No. 723,679. (No model.)

To all whom it may concern:

Be it known that I, ALBERT C. CALKINS, of Los Angeles, in the county of Los Angeles and State of California, have invented a new and 5 useful Improvement in Cupel-Machines, of which the following is a specification.

In assaying by cupellation the alloy of precious metal is placed in a shallow vessel made of bone-ash and is heated in a current of air 10 which oxidizes the lead and other impurities and allows them to be absorbed by the vessel of bone-ash, while the gold or silver remains behind as refined metal.

My invention is in the nature of a simple 15 and practical little machine whereby I am enabled to rapidly compress the bone-ash into the form of cupels or shallow vessels in a convenient and economical manner; and it consists in the peculiar construction and arrangement 20 of the machine, which I will now proceed to describe with reference to the drawings, in which—

Figure 1 is a perspective view of the entire machine. Fig. 2 is a detail vertical section 25 through the plunger and compression-chamber. Fig. 3 is a plan view, and Fig. 4 a detail, of the false bottom.

A is a metal disk with four circular holes a through it, forming the compression-chamber, in which the cupels x are successively formed. The disk A has another rotary adjustable disk B placed beneath it, in close contact therewith and forming a false bottom. The disk B has (see Fig. 4) a single circular 35 hole a' through it of larger size than the holes a in the disk A above. Both the disks A and B are arranged to turn freely on a vertical standard D, rising from a base C, and are held at a suitable height on the standard by jam- 40 nuts d . In the lower edge of disk A there are formed at distances equal to the spaces between the cells a four notches a^2 , into which there catches the end of a spring-pawl b . This disk B is also provided with a handle 45 b' for turning it. Fixed on the base C in upright position beside the standard D there is another standard F, having a lug or shoulder f projecting beneath the edge of the lower disk B.

50 Bolted to the upper ends of the standards D and F there is a metal frame E, held firmly

onto the tops of said standards by nuts d' and f' at top and bottom of said frame. This frame is bored vertically to form a circular chamber in it corresponding to the cells a of the disk A, and in this chamber there reciprocates a circular plunger J, having a rounded lower end and whose top is loosely pivoted to a downward projection from the head of a long hand-lever I. This lever has two stop-shoulders i and i^2 and is fulcrumed at i^3 upon a cross-bolt passing through slots l in the upper ends of the two links L, which in turn at their lower ends are loosely jointed by trunnions or otherwise to the opposite sides of frame E. Connecting with the fulcrum-bolt i^3 there is a short horizontal bar H, having a bearing h for the lever-stops i i^2 to strike against. This bar H at its outer end is jointed to a vertical link G, that in turn at its lower end is jointed to the end of frame E.

K is a hopper for pulverized bone-ash from which the cupels are made. This hopper is mounted upon a support K', rising from the base C, and the bottom of said hopper is open 75 and rests closely upon the upper surface of the upper disk A. A wheel k , with a rubber rim, is journaled in the bottom of the hopper and is rotated by contact with the traveling disk, so as to stir or agitate the bone-ash and insure a positive feed down into the cells of the subjacent disk as they pass under the same.

The operation of my machine is as follows: The cells a are filled automatically, as just 85 described, and their contents are retained by the imperforate portion of the subjacent disk B. When a cell is filled and brought by a handle b' under the chamber in frame E and in registration with its plunger J, the handle 90 I is up in the dotted position No. 1 and is brought down to the full-line position shown in Fig. 1, which compresses the bone-ash into a cupel x , Fig. 2. The handle b' is then turned to the right from a central position to 95 the position shown in full lines in Fig. 1, which brings the opening in the disk B immediately under the cupel x , and the lever I is then carried down farther to the dotted position No. 3 and the cupel is discharged 100 through both the disks A and B and drops upon the base C. The handle I is then raised

to its highest position, No. 1, which withdraws the plunger from both disks A and B, and the handle b' is then turned to the left from the full-line position, Fig. 1, through a quarter-revolution, and this through the spring-pawl b turns disk A and brings a freshly-filled cell a beneath the plunger for a repetition of the operation.

In the compressing operation the strain of the lever I near the edge of the disks A and B is borne on the shoulder f, so as to relieve the vertical axis of said disks.

To make larger or smaller cupels, different disks A are provided, which have such varying thickness or size of holes as may be desired. The plunger is also made of different diameters to correspond, and the hole in the plunger-frame is bushed to correspond.

With regard to the action of the lever I this is both peculiar and important. When the lever I is brought down, the leverage constantly increases to compress the cupel until the joint y passes directly under the bolt z³, which up to this time has been the fulcrum; but when this point has been reached the lever I changes its character, so that its former fulcrum becomes a movable part and a new fulcrum farther away from the plunger comes into play, for the stop-lug i² then bears against the bolt h, which becomes the fulcrum and the bolt i³ moves down in the slot l. The result is that the cupel is compressed with a powerful strain during the middle of the stroke of lever I and by the last part of the descent of the lever is quickly pushed through the bottom of the machine by a more rapid movement.

Having thus described my invention, what I claim as new, and desire to secure by Letters 40 Patent, is—

1. A compressing-machine having a plunger and a lever jointed to the plunger and having two separate fulcrum-bearings, one of which is located in a slotted bearing near the plunger and comes into action during the first

part of the stroke to give a powerful compression, and the other of which is located more remote from the plunger and comes into action during the last part of the same stroke of the lever to make a discharge of the object compressed by a continuation of the same stroke of the lever substantially as described.

2. A compressing-machine, consisting of a rotating disk with cells, an independently-rotating false bottom having a hole through it and connected with the disk above by a pawl, and a plunger, and plunger-guide substantially as and for the purpose described.

3. A compressing-machine, consisting of a rotating disk with cells, an independently-rotating false bottom with a hole through it, means for locking the two together, and also for turning them, a reciprocating plunger, and a shoulder resting beneath and in contact with the disks below the point where the compressing strain is applied substantially as and for the purpose set forth.

4. The combination with a base having two upright standards, one having a pair of rotating disks with cells as described, and the other a shoulder-rest for the edge of the disks, a frame rigidly connected to the tops of said standards and having a guide-chamber for a plunger, and a reciprocating plunger working therein substantially as and for the purpose described.

5. A compressing-machine, comprising a base with two standards D and F, the two rotating disks A and B connected together by a pawl, the frame E connected to the tops of the two standards and having a chamber for the plunger, the links L, bar H, and link G jointed as described, and the lever I with stops i i² and having a plunger loosely connected thereto as described.
